UNITED STATES PATENT OFFICE.

WILLIAM NEHRING, OF CINCINNATI, OHIO, ASSIGNOR TO THE QUEEN CITY MALLEABLE IRON COMPANY, OF SAME PLACE.

VEHICLE-WHEEL.

SPECIFICATION forming part of Letters Patent No. 257,744, dated May 9, 1882.

Application filed February 20, 1882. (No model.)

To all whom it may concern:

Be it known that I, WILLIAM NEHRING, of Cincinnati, Hamilton county, Ohio, have invented a new and useful Manufacture of Iron 5 Wheels, of which the following is a specification.

My invention relates to an improved manufacture of malleable-iron wheels, designed particularly for wheelbarrows and trucks for use 10 in foundries, furnaces, factories, and like establishments, in blast-furnace buggies, &c.

In the accompanying drawings, Figure 1 is a perspective view of a wheel embodying my 15 invention. Fig. 2 is an axial section of the same. Fig. 3 is an inner profile of one section of the hub and a portion of the attached skeleton. Fig. 4 is an internal profile of the other hub. Fig. 5 is an axial section of that form of 20 my hub which has a metal core. Fig. 6 is a transverse section of the same on the line xx , Fig. 5. Fig. 7 is a perspective rear view of one of the core-sections.

The rim A and spokes B are all cast in one 25 integral piece called the "skeleton" or "spider."

The hub consists of two similar hollow truncated cones, C C', having flanges D, of which one or both are formed with notches d to receive the inner ends of the spokes. The said 30 spokes and flanges are perforated, as at b and d', for the reception of rivets E, uniting together these three castings, which constitute the wheel.

Axial orifices F receive either a shaft driven 35 tightly into the hub, so as to revolve with the same, or a non-rotary axle upon which the wheel revolves. In the latter case the walls f of said orifice, which come in contact with the axle, are preferably cast on a chill for greater 40 durability and service.

The spider A B and hub-cones C C' are preferably cast of "strict white" iron and annealed sufficiently to render them malleable, and yet so as to preserve intact the chill or hardened journal-bearings f. The separation from one 45 another of the inner extremities of the spokes renders the spider exempt from strain incident to contraction in setting.

Where the wheel is wanted for uses which will subject it to severe treatment the interior 50 of the hub may be re-enforced by a core or filling, G, of cast-iron. A longitudinal groove, g, in the said core's periphery may receive a tongue, c, on the interior of one of the cones, C.

I claim as a new article of manufacture— 55

1. The wheel of malleable cast-iron, composed of spider A B, having the inner extremities of its spokes without direct cast connection, and secured by rivets E between the flanged hollow cones or frustums C C', substantially as set forth.

2. In described combination with the spider A B, cones C C', and rivets E, the core G, whose groove g receives a tongue, c', that projects from the interior of one of the cones, for 65 the purpose designated.

3. The wheel of malleable cast-iron, composed of spider A B, having the inner extremities of its spokes without direct cast connection, and occupying notches d in flanges D of 70 the bottom frustums, C C', to which they are secured by bolts or rivets E, substantially as set forth.

In testimony of which invention I hereunto set my hand.

WILLIAM NEHRING.
